UNITED STATES PATENT OFFICE.

CHARLES J. VAN DEPOELE, OF CHICAGO, ILLINOIS.

ELECTRIC LAMP.

SPECIFICATION forming part of Letters Patent No. 291,651, dated January 3, 1884.

Application filed April 3, 1883. (Model.)

To all whom it may concern:

Be it known that I, CHARLES J. VAN DEPOELE, of Chicago, in the county of Cook and State of Illinois, have invented new and useful Improvements in Electric Lamps for Continuous Currents; and I hereby declare that the following is a full, clear, and exact description thereof, reference being had to the accompanying drawings, which form a part of this specification.

This invention relates to certain new and useful improvements in the construction of electric lamps of the arc type; and the invention consists in the peculiar construction, combination, arrangement, and operation of parts, whereby a perfectly steady feed of carbon is obtained, as more fully hereinafter explained, reference being had to the drawings annexed to and forming a part of this specification.

Figure 1 is a front view of the feeding mechanism of the lamp, the lower portion of the lamp being omitted, as any of the ordinary constructions may be followed. Fig. 2 is a side view. Fig. 3 is a view the reverse of Fig. 1. Fig. 4 is a horizontal section on the line of the axis of the magnets in Fig. 1. Fig. 5 shows the circuits. Fig. 6 is a top plan of the lifter. Fig. 7 is a detail showing the escapement which moderates the descent of the carbon-carrying rod. Fig. 8 is a view in elevation, showing the general arrangement and construction of my improved lamp.

Fig. 1 is a front view of the mechanism of the lamp, in which is shown the electro-magnets A and B, A being in the main and B in the derived circuit. C C are the cores of the electro-magnets. E E is the iron armature, pivoted at its center, and acted upon by the electro-magnets A and B. F is a sleeve slipped on the upper carbon rod, resting with its under end upon the armature-shaft. On the upper part of said sleeve is a plate, F², having four projecting studs, upon which rest the lifter or clutch, which is composed of two brass plates, G G', connected together by an elastic plate, d, upon their lower sides, and provided at the center of said combination with two steel jaws, a b, as shown in Fig. 6. H H are two trip-screws, intended to open the lifter when the sleeve F moves downward by separating the sections of which it is composed.

Said trip-screws are also provided with springs e, slipped upon them, and held down by proper nuts, so that when the sleeve F moves upward the lifter is pressed down in the center by said springs, (instead of being pulled upward and opened transversely by the trip-screws H H,) causing the jaws to hold the carbon rod and to lift the same when F moves up. I is an adjustable contact-screw, adapted to give passage to the the derived circuit in the magnet B. J is a screw intended to adjust by means of a spring the upward pressure of the armature K, and thus to regulate the speed of the interruption. K is an armature intended to produce the interruptions of the derived circuit in the electro-magnet B. L is an angle-piece attached to B, and carrying the insulated screw I. M and M' are the top and bottom plates of the top part of a lamp. P and P are pivot-screws carrying the armature E E. Q Q is the insulation of the different parts. S S are the supports to P and P and to the armature E E; P^o, positive pole; N^e, negative pole. O O is the lower frame of lamp, connected to negative binding-post, as seen in Fig. 5. U is a small piece of iron communicating vibrations to K.

Fig. 2 is a side view of the lamp mechanism. So showing the magnet B. E E are the ends of the armature. P P are the pivot-screws on which the armature E E oscillates. S S are the supports to P P and E E. The vibrating system consists of the piece of iron U, intended to bring magnetism up to K, which, on the passage of the current, will be attracted, thus breaking contact with I, thus interrupting the current in the electro-magnet B, when K will rise again and complete the circuit. By means of J and its spring J', K can be made to vibrate with more or less rapidity. There are two circuits around the core of the electro-magnet B, both derived between the arc. One coil has the current closed constantly, while in the other the current is interrupted, as above stated. The vibrations are communicated by the core C to the armature E E, which actuates the feed.

Fig. 3 is a rear end view of the mechanism, showing the soft-iron armature E E, with its central shaft, D, upon which rests the sleeve F when E E is oscillated or moved toward the center of the core C in magnet A. It will be

seen that the sleeve F will be raised by the action of the shaft D, which is provided with a flat bearing extending a certain distance from the center of motion, as seen in Fig. 4.

5 The positive pole is insulated from the plate M' by insulation Q. V is the carbon rod.

Fig. 4 is a horizontal section through the electro-magnets A and B, through the armature E E, and the central shaft, D. C C are the iron magnet-cores. E E and E E are the double armatures, secured at their centers to the ends of the cast-iron shaft D, which is provided at its center with a circular opening large enough not to touch the carbon rod V. 15 As will be seen, D has in its central part an extension, which forms a seat for the sleeve F. The seat extends from the center of motion so far that when E E moves at its extremity, say, one-quarter of an inch, the seat will only move 20 about one-sixteenth, carrying with it the tube F, thus raising the upper carbon. E E and E E are rigidly attached to the shaft D, which is pivoted on the pivots P P, supported by S S.

25 Fig. 5 shows the circuits in the lamps, as follows: The current enters at P^o to the main electro-magnet A. The current follows the coil of this electro-magnet to its inside terminal, which is connected or soldered to the 30 brass ends of A, which is in turn secured to plate M', and plate M' is in electrical contact with the rod V through the brass or copper spring V', secured to M', and pressing tightly 35 against the rod V. The current passes down the top carbon to the lower one, from the lower carbon to the frame O, whence the current passes to negative pole by the copper conductor O', thus completing the main circuit. The derived circuit is completed as follows: 40 The electro-magnet B is wound with two independent coils of high resistance. One of the inner terminals is permanently connected to the end of the electro-magnet B at 1, which is positive. The inner terminal of the next coil 45 is connected to the insulated screw I, so that when K strikes I this terminal is also positive, while both outside terminals of the respective coils are connected together at 3, and led by a suitable conductor to the negative binding-post at 4, thus completing one circuit, one coil having a steady current to act upon the core C, while the second coil will have its current interrupted by the vibrator K. Said interruptions act also upon the core C, which in 55 turn react upon E E with a force corresponding to the length of the arc.

Fig. 6 shows the lifter or clutch, as seen at its top, composed of the two brass plates G G'. a b are the steel jaws. A B are the two magnets, and M' is the bottom plate.

60 Fig. 7 shows the clock-escapement intended to moderate the descent of the top rod, V.

Having described the different combinations and parts of my lamp, I will now proceed to 65 explain the operation of the same.

The course of the current through the lamp is as follows: The main current enters at the

positive binding-post, thence to the main electro-magnet A, thence to the lower plate, M', thence through the brush V' to upper carbon rod, thence through carbons to the frame O, thence to negative binding-post, and to line. The shunt-circuit includes the electro-magnet B, that is wound with two separate coils, is of relatively high resistance, and starts from the 70 core thereof, which, being in electrical connection with the plate M', is always positive. The wire or wires composing the said circuit are wound separately upon a single core and united at a point close to the exterior of the 75 magnet, from whence a single wire leads to the negative binding-post, completing the circuit.

In establishing the current by connecting the posts P^o and N^e to the respective terminals of a source of electricity, the main electro-magnet A will become excited, and, acting by both ends of the core C, will draw upward to its center the nearest end of the double armature E E. In so doing the sleeve F will be 90 raised correspondingly, and with it the lifter G G', which will carry the rod V, thus separating the carbons and producing the arc. Thus far the electro magnet B has not come into play; but soon the carbons will burn 95 away and more current will be forced through the coils of B. At this moment the core of B will become excited, and the piece U will attract the vibrator K, interrupting the current in one of the coils B. In the second coil B, the 100 derived circuit being continuous, the core C will be more strongly magnetized, and the vibrations will become stronger and more determined with the increase of distance between the two carbons, so that the combined action 105 of the steady and the interrupted currents in both coils of the electro-magnet B will tend to draw the armature E E toward the center of its core C, thus oscillating the shaft D and tending to bring said shaft with its seat in a 110 horizontal position, lowering the sleeve F, and with it the lifter G G', which will presently strike in its middle part on the heads of the trip-screws H H. Any farther downward motion of the sleeve F will open the jaws of 115 the said lifter, and thus allow the top carbon to feed down. As soon as the proper arc is established, the current will be weakened in the coils of the electro-magnet B, and the double armature will again obey the main electro-magnet A, and stop the feed by lifting or raising the sleeve F and lifter G G'. A moment 120 comes after the lamps have been well adjusted when the electro-magnet A and the electro-magnet B are constantly trying to overbalance 125 each other, and, since the double armature is constantly vibrating, the least downward motion will allow the lifter to touch the trip-screws H H and open its jaws, allowing the carbon rod to come through about a hair at a 130 time. This is caused by the vibrations produced in the armature E E by means of the interrupted derived circuit. This oscillating motion of the armature is extremely rapid, so

that the lifter never opens longer than for a fraction of a second at a time. The rod is thus prevented from making any fast downward movement, and the feed of the carbons thus produced is imperceptible, and the result a perfectly steady light. The descent of the top carbon rod is further rendered more gentle by the escapement T, which helps to secure a gradual and uniform downward feed. In some cases the derived circuit around the core C in the electro-magnet B is interrupted in both coils, instead of in only one; or the two coils may be replaced by a single coil. This is done so as to prevent the fine wire being burned in case of an abnormal arc. The vibrator K will in this case make and break circuit with violence; but, since the current will not be flowing continuously, the fine wire will be saved, whereas in case of the continuous current said fine wire magnets would be destroyed.

It will be seen that the interruptions in the derived-circuit electro-magnet has two aims, the first being to produce a rapid motion in the armature E E, so as to render its action more sensitive and sharp, and to react upon the feed of the top carbon rod. The second aim of the interruptions in the derived circuit is to save the fine-wire magnet in case of an accidental long arc.

30 I do not limit myself to the above-described peculiar method of producing said interruptions in the derived circuit, as many different devices can be made to accomplish the same result without departing from the spirit of my invention, and so can different contrivances be used, in combination with the vibrating armatures, to act upon the feed mechanism of the carbons without changing my aim.

In order to utilize the escapement for the purpose hereinbefore described, one side of the carbon-carrying rod V is toothed, as at e, and one of the wheels of the train W engages with the teeth upon the rod, and, through its connections with the other wheels of the train, brings into action the escapement.

What I claim as my invention, and desire to secure by Letters Patent, is—

1. In an electric-arc lamp, an electro-magnet located in the main circuit, in combination with an electro-magnet having two independent coils wound in the same direction upon its core, both coils being in a derivation between the carbons, one of said coils having its circuit closed continuously, and the other having its current interrupted by a proper circuit-breaker or vibrator, both coils coacting upon said core to produce vibratory movements in the armature and feeding devices of the lamp, substantially as set forth.

60 2. In an electric-arc lamp, an electro-magnet in the main circuit and an electro-magnet having two independent coils wound in the same direction upon its core, both of said coils being located in a shunt around the arc, the circuit through one of said coils being closed continuously, and that through the other being continuously broken by a suitable

circuit-breaker included therein, said electro-magnets acting upon a compound armature having a central shaft provided with pivots, 70 upon which said armature will oscillate, actuating the carbon-feeding devices under the influence of the above-named electro-magnets, substantially as set forth.

3. In an electric-arc lamp, an electro-magnet located in a shunt around the arc, and having two independent coils upon its core, the circuit through one of said coils being closed continuously, and that through the other being continuously made and broken by a suitable circuit-breaker included therein, both said coils being wound in the same direction and coacting upon said core, substantially as set forth.

4. In an electric-arc lamp, a compound armature consisting of a central shaft of iron, D, having bars of soft iron, E, centrally attached to its extremities, and a seat provided upon its middle portion, upon which a sleeve rests, said sleeve supporting the carbon holding and feeding mechanism of the lamp, and operated by the oscillations of said shaft under the influence of the steady main electro-magnet A and pulsating shunt-magnet B upon the said bars E, the shaft D being provided 95 with a circular opening in its center for the carbon rod, substantially as set forth.

5. In an electric-arc lamp, the compound armature E, in combination with the sleeve F, slipped loosely over the carbon rod V, the 100 sleeve F, provided with a plate, F', and projecting studs supporting the lifter G G', and proper means for raising and lowering the sleeve F, so as to make the lifter either hold or release the carbon rods, substantially as 105 described.

6. In an electric-arc lamp, the clutch or lifter G G', made of two parts, and united in its center by a flexible or elastic band of metal, adapted to hold the parts together, and provided with steel jaws a b, in combination with the trip-screws H, so disposed, in conjunction with the clutch, that when said clutch is raised from said screws the jaws a b will close upon the rod V, holding and raising the same 115 during the upward movement of the sleeve F, when F moves downward the reverse taking place, the lifter striking the screws H, opening the clutch, and allowing the rod V to move downward, as above specified, and for the purposes described.

7. In an electric-arc lamp which is provided with a serrated carbon-carrying rod and devices for automatically feeding the same by means of the oscillations of a centrally-pivoted armature, actuated by the cores of a steady main and pulsating shunt magnet, a train of gear-wheels, and an escapement, substantially as and for the purposes set forth.

CHARLES J. VAN DEPOELE.
